UNITED STATES PATENT OFFICE.

PAUL H. COLEMAN, OF BONHAM, TEXAS.

HINGED CONNECTION.

1,135,359.

Specification of Letters Patent.

Patented Apr. 13, 1915.

Application filed June 5, 1914. Serial No. 843,146.

To all whom it may concern:

Be it known that I, PAUL H. COLEMAN, a citizen of the United States, residing at Bonham, in the county of Fannin and State of Texas, have invented certain new and useful Improvements in Hinged Connections, of which the following is a specification.

My invention relates to a new and useful hinged connection, and its object is to provide a hinged connection between a door and a door jamb, or between any swinging member and the stationary member by which it is supported, said connection being such that the door (or other swinging member) will be positively limited to angular motion through an arc of any desired magnitude.

A still further object of the invention is to provide a device of the character described, that will be strong, durable, efficient and simple and comparatively inexpensive to produce, also one in which the several parts will not be likely to get out of working order.

With the above and other objects in view, the invention has relation to certain novel features of construction and operation, an example of which is described in the following specification and illustrated in the accompanying drawing, wherein:

Figure 1 is a view showing in elevation two members, forming with each other an acute angle, which is the minimum angle they are permitted to assume by my hinged connection. Fig. 2 is a horizontal sectional view, the section being taken upon the line $x-x$ of Fig. 1. Fig 3 is a view showing the reverse or rear side of my composite hinge member.

Referring now more particularly to the drawing, wherein like reference characters designate similar parts in all the figures, the numeral 1 denotes two members which are connected by my novel composite hinge, one of said members being considered as stationary and the other swinging.

My composite hinge comprises two vertically spaced pairs of hinge members 2, and a third pair of hinged members 3 interposed between the others. The members 2 of each pair being respectively fastened by screws (or other suitable means) to the adjacent edge faces of the members 1 and have connection between two of their edges in the usual manner through a pintle 4. The other two edges of each pair of members 2 engage

vertical pintles 5 which establish a connection between the upper and lower pairs of members 2. The members 3 are respectively hinged upon the pintles 5, and pivotally connected through a pintle 6. The portions of the members 3 which engage the pintles 5 are cut away to permit tongues 7 to engage said pintles, said tongues being formed integral with hinge plates 8 which are mounted upon corresponding side faces of the members 1.

The members 2 perform the functions of ordinary hinges; namely, to establish a vertical axis between the two members 1 about which one of said members may swing, supported by the other. The members 3 serve to limit the arc through which the swinging member may be displaced. Thus it is seen in Fig. 2 that there has been established between the members 1 the minimum angle permitted by the members 3.

As the swinging member 1 is shifted into the position in which it is alined (or flush) with the stationary member 1, it is desired to have the members 3 seat themselves against the edge faces of the members 1, the pintle 6 coming into an alinement with the pintles 4. To insure this motion of the members 3, it is necessary to prevent said members coming into a perfect alinement as the swinging member 1 reaches the limit of its angular motion by forming the contiguous sleeve-forming portions of the members 3 with interfitting shoulders as indicated at 90 9, which shoulders will seat one upon another (see Fig. 3) to prevent a perfect alinement of the members 3. It is preferred to mount small washers 10 upon the pintles 5 between the members 2 and 3, so that there 95 will be a freedom of motion between said members. While it is preferred to so extend the pintles 5 that they may be engaged by sleeves formed upon the members 3, it is to be understood that the pintles 5 may if 100 desired be supported integral by the members 8, in this case terminating flush with the tops and bottoms of the members 3.

The invention is presented as including all such modifications and changes as properly come within the scope of the following claim.

What I claim is:

In a device of the character described, the combination with a swinging member and a stationary member supporting the same, two spaced pairs of pivotally connected hinge

plates respectively secured to the adjacent edge faces of the swinging and stationary members, a third pair of hinge plates interposed between the other two pairs and pivotally connected, and pintles upon which the plates comprising the third pair are respectively hung, the end portions of said pintles being engaged by the spaced hinge plates.

Copies of this patent may be obtained for five cents each, by addressing the "Commissioner of Patents, Washington, D. C."

In testimony whereof I have signed by name to this specification in the presence of 10 two subscribing witnesses.

PAUL H. COLEMAN.
